UNITED STATES PATENT OFFICE.

ALBERT H. AMMANN, OF CHICAGO, ILLINOIS, ASSIGNOR TO JOSTAM MANUFACTURING CO., COMPOSED OF WALTER R. JORGENSEN, W. D. STANNARD, AND A. H. AMMANN, OF CHICAGO, ILLINOIS.

RECOIL PAD FOR GUNS.

Application filed May 21, 1926. Serial No. 110,587.

This invention relates to recoil pads for guns, and is particularly concerned with improvements in the type of recoil pad which comprises a relatively hard base plate for attachment to a gun stock and a relatively soft rubber cushion carried by the base plate, such relatively soft cushion being provided with a plurality of transverse air pockets open to the atmosphere at the lateral margins of the pad.

Among its objects, the present invention contemplates the provision of a recoil pad of the general type mentioned, wherein the air pockets and the webs and walls which define such air pockets are so conformed and arranged as to insure a maximum pneumatic cushioning effect in a pad which has extremely resilient rear vertical edges, the rear face of which readily accommodates itself to fit the shoulder of a marksman, and which in operation delivers the cushioned force of recoil straight back to the shoulder of the marksman.

Another object of the present invention is the provision of a pad of the general type hereinbefore mentioned in which the relatively soft rubber cushion is provided with self-closing openings for the insertion of the screws whereby the base plate of the pad is attached to the gun stock, these self-closing screw insertion openings enabling me to dispense with the closure plugs which heretofore have been necessary when the soft rubber pad has been vulcanized or otherwise permanently secured to its base plate prior to the attachment of the recoil pad to a gun.

Other features, objects and advantages of the present invention will appear as the following detailed description progresses.

In the accompanying drawing Figure 1 is a side elevational view of my improved recoil pad as the same appears when attached to a gun stock.

Figure 2 is a central vertical sectional view of the elements shown in Figure 1.

Figure 3 is a horizontal sectional view taken on the line 3—3 of Figure 1.

Figure 4 is a horizontal sectional view taken on the line 4—4 of Figure 2.

Figure 5 is a rear elevational view of the recoil pad, and

Figure 6 is a view corresponding to Figure 1, but illustrating the distortion of which the

walls, webs and air pockets of the rubber cushion are capable.

Similar characters of reference refer to similar parts throughout the several views.

In the drawing 10 represents a gun stock provided with a plane rear face 11 to which the improved pad of my invention is attached by screws, as will be more fully hereinafter explained.

The recoil pad comprises a relatively hard base plate 12, preferably formed of hard rubber, and a cushion 13 which is preferably formed of a good quality of soft rubber. The base plate 12 and the cushion 13 constitute a unit. They are preferably vulcanized together. It is practical, however, to cement the soft rubber cushion to the base plate, if desired. The rear surface of the cushion, that is the surface which is intended to bear against the shoulder of the marksman, may be a plane surface, if desired, but is preferably somewhat convex, being curved from side to side as is clearly illustrated in Figures 3 and 4. By reason of this convexity I am enabled without weakening the cushion to bring its rear vertical edges 14—14 very close to the first line or row of elongated air pockets presently to be mentioned, this arrangement affording and insuring great flexibility at such rear lateral edges.

Formed in the cushion 13 are two lines or rows of transversely extending air pockets 15—15 and 16—16, each of said air pockets being open at both ends to the atmosphere. It will be noted that each of said air pockets is elongated vertically, and that the pockets 15—15 of the first line or row are staggered with respect to the air pockets 16—16 of the other line or row. If desired, cylindrical air pockets 17—17 may be formed in the cushion adjacent the extremities of the first line or row of air pockets to afford greater resiliency near the heel and toe of the pad and to improve the general appearance of the pad.

The two rows of air pockets hereinbefore mentioned virtually divide the cushion into three rather distinct though integral walls, namely the rear wall *a*, the intermediate wall or partition *b* and the front wall *c*, the central wall or partition being connected to the rear wall by horizontal webs *dd* and to the front wall by similar hori-

zontal webs *ee*, the webs *dd* being staggered with respect to the webs *ee*.

I have found from practical experience that it is very desirable that a recoil pad of the general type to which my invention relates should be extremely resilient at its rear vertical edges, and should be capable of conforming itself laterally to bear smoothly and snugly against the shoulder of a marksman.

10 It has been found that if a pad does not have very resilient rear lateral edges the shoulder of the marksman is very apt to be bruised along the line of one or the other of these edges, depending upon whether the marksman is a right-hand or left-hand shooter. Furthermore, very few marksmen in bringing a gun pad to their shoulder place the same in exactly the theoretically correct position against the shoulder, or hold their gun

15 at precisely the theoretically correct angle with respect to the shoulder. For these reasons it is desirable that a gun pad be capable of conforming itself laterally best to fit against the shoulder of the marksman. Due to the particular conformation and arrangement of the cushion walls, webs and air pockets hereinbefore explained, the recoil pad of the present invention is characterized by extremely flexible rear lateral edges, and is capable of conforming itself laterally as herein explained.

Under the recoil of the gun the walls, webs and air pockets of the soft rubber cushion are distorted substantially as illustrated in Figure 6, this distortion serving to reduce the cross sectional area of the air pockets and expelling air therefrom and thereby increasing the cushioning effect of the recoil pad by reason of the fact that much of the energy of the recoil is absorbed by the frictional resistance which the walls of the open air pockets exert upon the expelled air.

The pad of my present invention is adapted to be secured to the gun stock by screws 18 which extend freely through apertures in the base plate 12. I prefer to locate small metal washers 19 adjacent the base plate apertures and concentric therewith to receive the thrust of the screws 18, the said washers being preferably imbedded in the cushion 13 at the time it is molded or at least before it is vulcanized or otherwise permanently secured to the base plate.

Formed in the cushion 13 and extending therethrough from front to rear are conical openings 20-20, each of said conical openings being coaxial with one of the base plate apertures aforesaid and having its small end at the rear surface of the cushion. The smaller end of each of the conical openings 20 may be very small in diameter, so small in fact that the openings at the rear face of the pad need not be plugged or otherwise closed. Preparatory to securing my

improved pad upon a gun stock, each of the screws 18 is forced, point first, through the smaller end through one of the conical screw insertion openings 20, the rubber bounding the said screw insertion opening stretching to permit the passage of the screw and then reassuming its normal position. It will thus be seen that the screw insertion openings of the pad of the present invention are virtually self-closing. Heretofore when screw insertion openings have been provided in recoil pads of the general type to which my invention relates, it has been necessary to provide rubber plugs for closing the said screw insertion openings after the pad has been applied to a gun stock. I have found that in the case of my improved pad the rear or exposed ends of the screw insertion openings may be of such small diameter that they may be considered closed so far as practical consideration is concerned.

Having thus illustrated and described the preferred embodiment of my invention, what I claim is new and desire to secure by Letters Patent of United States is:

1. A recoil pad for a gun stock comprising a base plate, a soft rubber cushion carried by the base plate, two vertical rows of vertically elongated open-ended transverse air pockets formed in said cushion, the pockets of one row being staggered with respect to the pockets of the other row, the ends of the rear row of pockets being located immediately adjacent to the lateral rear edges of the cushion, the rear surface of the cushion being curved convexly from side to side.

2. In a recoil pad, a resilient cushion comprising a front wall, an intermediate wall and a rear wall, said intermediate wall being connected with each of the other walls by transverse webs, the webs connecting the intermediate wall with the front wall being staggered with respect to the webs which connect the intermediate wall with the rear wall.

3. In a recoil pad, a resilient cushion comprising a front wall, an intermediate wall and a rear wall, said intermediate wall being connected to both of the other walls by transverse webs, the webs connecting the intermediate wall with the front wall being staggered with respect to the webs which connect the intermediate wall with the rear wall, and a relatively hard base plate affixed to said cushion, said base plate having apertures for the passage of retaining screws and said cushion having aligned apertures to receive the heads of said screws, said latter apertures being tapered to substantial closure at the rear face of said cushion.

In witness whereof, I hereunto subscribe my name this 17 day of May, 1926.

ALBERT H. AMMANN.
